UNITED STATES PATENT OFFICE.

CHARLES A. WHITE, OF BUFFALO, NEW YORK, ASSIGNOR, BY DIRECT AND MESNE ASSIGNMENTS, TO ECONOMIC PRESS DELIVERY COMPANY, OF BUFFALO, NEW YORK, A CORPORATION OF NEW YORK.

SHEET-DELIVERY ATTACHMENT FOR PRINTING-PRESSES.

1,141,856.

Specification of Letters Patent.

Patented June 1, 1915.

Application filed July 22, 1909. Serial No. 508,921.

To all whom it may concern:

Be it known that I, CHARLES A. WHITE, a citizen of the United States, residing at Buffalo, in the county of Erie and State 5 of New York, have invented a new and useful Improvement in Sheet-Delivery Attachments for Printing - Presses, of which the following is a specification.

This invention relates to sheet delivering 10 attachments for bed and cylinder printing presses of that type known as two revolution front delivery presses in which the impression is made during one revolution of the impression cylinder and the advance 15 movement of the reciprocating bed, and the printed sheet is removed from the cylinder and discharged from the press during the next revolution of the cylinder in the same direction and the return movement of the 20 bed, the sheet passing out of the press in the same direction in which it is fed to the press. In these presses, as ordinarily constructed, the oscillating fly takes the printed sheets 25 from traveling delivery tapes and piles them on a receiving table at the delivery end of the press. On account of the location of this receiving table over the inking mechanism, only space enough for a comparatively low 30 pile of sheets is afforded between the table and the fly and consequently it is necessary to frequently stop the press to remove the 35 printed sheets.

The primary objects of this invention are to produce a sheet delivering attachment 40 which can be applied to the ordinary two revolution front delivery presses at small expense and without material change in the press, and which is adapted to deliver the printed sheets onto a receiving table or device 45 that can be lowered as the pile of sheets increases in height, so as to maintain the top of the pile at substantially the same height and permit a large pile of sheets to accumulate before the pile has to be removed; and also to provide elevating means 50 whereby a wheeled table or truck can be raised to a position to receive the sheets directly from the fly and can be lowered as the pile increases in height until it rests on the floor, when it can be drawn away with the pile of sheets thereon and replaced by another receiving table or truck, so as to obviate the labor of lifting the sheets in taking them from the press.

In the accompanying drawings, consisting of three sheets: Figure 1 is a fragmentary elevation of one side of a two revolution front delivery printing press provided with a sheet delivery attachment and receiving table or device embodying the invention. Fig. 2 is an elevation of the opposite side thereof. Fig. 3 is a plan view thereof. Fig. 4 is a longitudinal sectional elevation thereof. Fig. 5 is a transverse sectional elevation thereof in line 5—5, Fig. 4. 65 Fig. 6 is a sectional elevation, on an enlarged scale, of the means for evening the pile of sheets on the receiving table or device.

Like reference characters refer to like 70 parts in the several figures.

A represents the frame, B the impression cylinder, C the reciprocating bed and D, d, d' the ink applying and spreading rolls of a two-revolution front delivery printing 75 press.

E represents the usual traveling delivery tapes which carry the printed sheets from the impression cylinder and from which the oscillating fly takes the sheets and piles them 80 on the receiving table. Ordinarily this fly is journaled on the frame at the point indicated at f in Figs. 1, 2 and 4, to oscillate from a position between the delivery tapes E to a position over the receiving table f', indicated by dotted lines, Fig. 4, which is located over the inking rolls D, but in providing the attachment constituting this invention the fly G is removed from this location and is journaled at the extreme front 90 end of the press on brackets H which are provided for the purpose and are secured to the opposite sides of the press frame, and an auxiliary set of tapes I is supplied for carrying the sheets from the main tapes to the 95 fly G. The fly may be oscillated in the usual way by a segment gear g, Fig. 2, on its shaft meshing with a toothed rack bar g' which is reciprocated by a cam g² and spring g³, it being only necessary to provide a rack bar 100 of suitable length to reach the fly in its new position at the end of the press. The auxiliary tapes I pass around wheels on the shaft i for the front ends of the main tapes and on a shaft i' journaled in the brackets H, the auxiliary tapes being driven by the main tapes, which latter are driven by the usual gearing i'. The auxiliary tapes are desirable

in that they allow more time for the ink to dry before the sheets are piled by the fly.

K represents a vertically movable table or device which is arranged at the front or delivery end of the press in position to receive the sheets directly from the fly G. Preferably the receiving table or device consists of a wheeled truck which is removably supported by elevating supports L on which the truck rests, see particularly Fig. 5. These elevating supports are movable vertically on stands M of suitable construction arranged at opposite ends of the truck, and are moved for raising and lowering the truck by vertical screws N which are journaled in the stands M and work in screw-threaded holes in the elevating supports L. The supports have guide parts engaging the stands M to hold the supports from being turned by the screws N. The screws N can be turned by hand wheels n connected to the screws by bevel gear wheels n', or by other suitable means.

In the operation of the press the truck K is placed between the stands M with the elevating supports L extending beneath the ends of the truck, and the screws N are operated to lift the truck to a suitable height to receive the printed sheets from the fly G. The fly operates to pile the sheets on the truck K and the truck is lowered from time to time as the pile of sheets increases in height, so as to maintain the top of the pile at a substantially constant level suitable to receive the sheets from the fly. When the truck has been lowered far enough to rest upon the floor, one of the elevating stands M is moved out of the way and the truck can then be wheeled away with the pile of sheets, and another truck put in its place and raised to the proper height to receive the sheets. In this way the press can make a long run, for instance, a whole day's run, before it is necessary to remove the sheets, and the sheets do not have to be lifted or handled in taking them from the press, so that a great deal of time and labor are saved in operating the press.

The described elevating means enables wheeled trucks of ordinary construction to be used, and as a plurality of trucks can be employed with the one elevating means the pile of sheets can be left on a truck as long as desired without interfering with the operation of the press or requiring each truck to be equipped with its own elevating means. Any other suitable means could be employed for thus raising and lowering the truck, and, if preferred, an ordinary paper tray could

be used on the truck and raised off of and lowered onto the truck by the elevating means instead of raising and lowering the truck itself.

O, Figs. 4 and 6, represents a device which is preferably provided for shifting the sheets as they are delivered to the receiving table, to keep the pile even. This device consists of a rock shaft provided with fingers to strike the sheets and journaled in arms p clamped on a cross rod p' connecting the brackets H. The shaft of the evening device is rocked by a cord p² attached to an arm thereon and wound about the shaft of the fly G. Any other suitable means could be employed for this purpose.

I claim as my invention:

1. The combination of oppositely arranged spaced standards which are supported in upright position, elevating supports which project toward each other from and are movable vertically on said standards, vertical screws journaled on said standards for raising and lowering said supports, said supports having guide parts engaging said standards, handles arranged to rotate at the outer sides of said standards and operatively connected to said elevating screws for turning the same, and a support for a pile of sheets adapted to rest on said elevating supports between said standards, said standards and screws being disconnected above the base portions of the standards so as to leave an unobstructed space between the standards for said sheet support and the pile of sheets thereon, substantially as set forth.

2. The combination with a support for a pile of sheets, of portable standards supported in upright position and movable into operative relation to the support, elevating supports movable vertically on said standards and having parts adapted to engage said support for the pile of sheets, each standard having mounted thereon separate and independent means for raising and lowering the elevating support on said standard, said means including an operating handle arranged at the outer side of the standard, said standards being disconnected above the base portions thereof so as to leave an unobstructed space between the standards for said sheet support and the pile of sheets thereon.

Witness my hand, this 17th day of July, 1909.

CHARLES A. WHITE.
